US0D1009562S

(12) **United States Design Patent** (10) Patent No.: **US D1,009,562 S**
(45) Date of Patent: ** Jan. 2, 2024

(54) **BLENDER JAR**

(71) Applicant: **WHIRLPOOL CORPORATION**,
Benton Harbor, MI (US)

(72) Inventors: **John W. McConnell**, St. Joseph, MI
(US); **Brandon T. Mock**, St. Joseph,
MI (US); **Aaron McNabb Evans**, St.
Joseph, MI (US)

(73) Assignee: **Whirlpool Corporation**, Benton
Harbor, MI (US)

(**) Term: **15 Years**

(21) Appl. No.: **29/883,564**

(22) Filed: **Jan. 31, 2023**

(57) **CLAIM**

We claim the ornamental design for a blender jar, as shown and described.

DESCRIPTION

FIG. 1 is a first side perspective view of a blender jar of the present disclosure;

FIG. 2 is a second side perspective view of the blender jar of FIG. 1;

FIG. 3 is a front perspective view of the blender jar of FIG. 1;

FIG. 4 is a rear perspective view of the blender jar of FIG. 1;

FIG. 5 is a first side elevational view of the blender jar of FIG. 1;

FIG. 6 is a second side elevational view of the blender jar of FIG. 1;

FIG. 7 is a third side elevational view of the blender jar of FIG. 1;

FIG. 8 is a fourth side elevational view of the blender jar of FIG. 1;

FIG. 9 is a top plan view of the blender jar of FIG. 1; and,
FIG. 10 is a bottom plan view of the blender jar of FIG. 1.
The broken lines depict portions of the article that form no
part of the claimed design.
